UNITED STATES PATENT OFFICE.

WILLIAM F. BAKER, OF KANSAS CITY, MISSOURI, ASSIGNEE OF THIRTY-FIVE ONE-HUNDREDTHS TO LULU A. BAKER, THIRTY ONE-HUNDREDTHS TO JOHN A. KEISTER, AND THIRTY ONE-HUNDREDTHS TO JOHN M. WILSON, ALL OF KANSAS CITY, MISSOURI.

PISTON AND CYLINDER LUBRICATOR.

1,288,800.

Specification of Letters Patent. Patented Dec. 24, 1918.

Application filed April 9, 1918. Serial No. 227,424.

To all whom it may concern:

Be it known that I, WILLIAM F. BAKER, a citizen of the United States, residing at Kansas City, in the county of Jackson and State of Missouri, have invented a certain new and useful Improvement in Piston and Cylinder Lubricators, of which the following is a specification.

My invention relates to improvements in piston and cylinder lubricators.

My invention is particularly adapted for advantageous use in explosive engines of the V-type having inclined cylinders, although it is well adapted for use on either vertical or horizontal engines.

In engines having inclined cylinders, the upper side of the piston and the upper inner side of the cylinder is liable to run dry, thereby causing undue heating and wear.

The object of my invention is to provide lubricating means with which a plentiful supply of oil may be evenly distributed over the wearing surfaces of the piston and cylinder.

My invention provides further a novel lubricating piston ring adapted for ready application to and removal from a piston.

My invention provides still further a novel lubricating ring adapted for ready application to or removal from the inner wall of a cylinder.

Other novel features of my invention are hereinafter fully described and claimed.

In the accompanying drawing, which illustrates my invention, in its preferred embodiment, as applied to an inclined cylinder and piston,

Figure 1 is a view partly in side elevation and partly in vertical section of an inclined cylinder and piston provided with my improvement.

Fig. 2 is an edge view of my improved lubricating piston ring.

Fig. 3 is an edge view of my improved lubricating cylinder ring.

Fig. 4 is a cross section on the line 4-4 of Fig. 3.

Fig. 5 is a cross section on the line 5-5 of Fig. 2.

Fig. 6 and 7 are outside views of the piston and cylinder lubricating rings respectively.

Similar reference characters designate similar parts in the different views.

1 designates an inclined cylinder of an explosive engine of the usual V type. 2 designates a piston reciprocative in the cylinder 1 and which is provided with the usual piston rings 3.

The cylinder 1 near its lower end is provided with an inner annular peripheral groove 4, which is adapted to communicate with an annular peripheral groove 5 on the piston 2, when the latter is at its limit of downward movement, as shown in Fig. 1. Preferably the groove 4 is located below the lower limit of travel of the outer or lower piston ring 3. The groove 5 is located below or at the outer side of the lowermost piston ring 3.

The function of the grooves 4 and 5 is to carry oil from the lower to the upper side of the piston 2 to prevent the upper side of the piston and the inner upper side of the cylinder from running dry, and to effect an equal distribution of the oil on the piston and bearing surfaces of the cylinder.

In order that the oil may be freely carried, in the grooves 4 and 5, from the lower side of the piston where there is usually an abundance of oil, I provide for insertion respectively in the piston and cylinder grooves 5 and 4, two lubricating devices shown in Figs. 2 to 7, comprising two-transversely divided channeled rings containing a suitable absorbent material, such as felt.

The lubricating device, which is fitted in the groove 5 of the piston, and shown in Figs. 2, 4 and 6, comprises a transversely divided ring 6 provided with an outer peripheral channel which is filled with an absorbent material 7, such as felt, which extends outwardly beyond the outer side of the ring 6, and which bears against the cylinder 1.

As shown in Fig. 6, the ends of the ring 6 are beveled so as to overlap each other, as are the ends of the divided ring of felt 7. By means of this construction the joint at the ends of the ring is broken, insuring a distribution of oil over the entire circumference of the cylinder wall.

The lubricating device which is fitted in the groove 4 of the cylinder 1 comprises a

transversely divided ring 8, which is provided with an inner peripheral channel filled with an absorbent material 9, such as felt, which bears against the piston 2.

5 As shown in Fig. 7, the ends of the ring 8 are beveled, so as to overlap each other, as are also the ends of the felt ring 9. This construction insures distribution of oil all around the piston.

10 The rings 6 and 8 are, preferably, of some resilient material, such as sheet steel or brass. The felt 9 extends inwardly beyond the inner side of the ring 8, as shown in Figs. 3 and 4. The inner edges of the channel ring 8 do not reach the piston 2 and the outer edges of the channel ring 6 do not reach the cylinder, thus avoiding any scratching or scoring of the piston or cylinder.

15 20 In applying the ring 8, it is compressed sufficiently to permit its insertion into the cylinder and then permitted to expand into the groove 4. The ring 6 is compressed so as to enter the cylinder 1 after being placed 25 in the groove 5, after which it is permitted to expand so that the felt 7 bears against the cylinder.

Oil upon the lower inner side of the cylinder will enter the felt 7 and 9 and being 30 absorbed thereby will be carried by capillary attraction around the piston 2. The felt 7 carried by the piston will carry the oil upwardly and will effect an equal distribution of the oil over the cylinder, while the 35 felt 9 will effect an even distribution of the oil over the piston 2.

I do not limit my invention to the structure shown and described, as modifications, within the scope of the appended claims, 40 may be made without departing from the spirit of my invention.

What I claim is:—

1. A cylinder having an inner annular peripheral groove, a piston reciprocative in 45 said cylinder and having a piston ring, the groove being located outside the limit of travel of the ring, and porous absorbent material in said groove bearing against said piston.

50 2. A cylinder having an inner annular peripheral groove, a piston reciprocative in the cylinder, a transversely divided ring mounted in said groove and having an inner peripheral channel, and porous absorbent 55 material in said channel bearing against said piston.

3. A cylinder having an inner annular peripheral groove, a piston reciprocative in the cylinder, a transversely divided ring in 60 said groove having an inner peripheral channel, and porous absorbent material in said channel and extending inwardly beyond the inner edge of the ring and bearing against said piston.

65 4. A cylinder lubricating device comprising

ing a transversely divided ring having an inner peripheral channel, and porous absorbent material filling said channel and extending inwardly beyond the inner side of the ring.

70 5. A cylinder lubricating device comprising a transversely divided ring comprising a single member having a circumference greater than a semicircle, having a peripheral channel on its outer side, and porous absorbent material filling said channel and extending outwardly beyond the outer side of the ring.

75 6. A cylinder lubricating device comprising a transversely divided ring having beveled ends adapted to overlap each other and having an inner peripheral channel, and porous absorbent material filling said channel and extending inwardly beyond the inner side of said ring.

80 7. A cylinder lubricating device comprising a transversely divided ring having beveled ends adapted to overlap each other and having an outer peripheral channel, and porous absorbent material filling said channel and extending outwardly beyond the outer side of said ring.

85 8. A cylinder having an inner annular peripheral groove, a piston reciprocative in the cylinder and having a peripheral annular groove adapted in the movement of the piston to communicate with the groove in the cylinder, and porous absorbent material in both of said grooves for carrying oil around the piston.

90 9. A cylinder having an inner annular peripheral groove, a piston reciprocative in the cylinder and having a peripheral groove, a transversely divided ring fitted in the cylinder groove and having an inner peripheral channel, a transversely divided ring fitted in the piston groove and having an outer peripheral channel, porous absorbent material filling the first named ring and bearing against the piston, and absorbent 105 material filling the second named ring and bearing against the cylinder.

100 10. A cylinder having an inner annular peripheral groove, a piston reciprocative in the cylinder, a transversely divided ring in 115 said groove having an inner peripheral channel and having beveled ends adapted to overlap each other, and porous absorbent material filling said channel and bearing against said piston.

11. A cylinder, a piston reciprocative therein having an annular peripheral groove, a transversely divided ring comprising a single member having a circumference greater than a semicircle fitted in said 125 groove and having an outer peripheral channel, and porous absorbent material filling said channel and bearing against said cylinder.

12. A cylinder, a piston reciprocative 130

therein having an annular peripheral groove, a transversely divided ring fitted in said groove and having an outer peripheral channel and beveled ends adapted to overlap each other, and porous absorbent material filling said channel and bearing against said cylinder.

13. A cylinder having an annular peripheral groove, a transversely divided ring fitted in said groove, a piston reciprocative in said cylinder having an annular peripheral groove adapted on the outstroke of the piston to communicate with the groove in the cylinder, the said ring having an inner peripheral channel, absorbent material in said channel bearing against said piston, a transversely divided ring fitted in the groove in the piston and having an outer peripheral channel, and porous absorbent material in the last named channel bearing against said cylinder.

14. A cylinder having an annular inner peripheral groove, a piston reciprocative in said cylinder having a piston ring and an annular peripheral groove at the outer side of said ring adapted at the end of the outer

stroke of the piston to communicate with the first named groove, said first named groove being disposed outwardly beyond the limit of movement of the piston ring, and porous absorbent material in both of said grooves and encircling the piston.

15. A cylinder having an inner annular peripheral groove, a piston reciprocative in said cylinder having a piston ring and an annular peripheral groove at the outer side of said ring adapted to communicate with the cylinder groove on the outstroke of the piston, the cylinder groove being outwardly beyond the limit of movement of the piston ring, a transversely divided ring fitted in the cylinder groove and having an inner peripheral channel, absorbent material filling said channel and bearing against said cylinder, a transversely divided ring fitted in the piston groove and having an outer peripheral channel, and porous absorbent material filling the last named channel and bearing against said cylinder.

In testimony whereof I have signed my name to this specification.

WILLIAM F. BAKER.
